UNITED STATES PATENT OFFICE.

RICHARD MERCER, OF LIVERPOOL, ENGLAND, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed March 12, 1921. Serial No. 451,903.

To all whom it may concern:

Be it known that I, RICHARD MERCER, a subject of the King of Great Britain and Ireland, and a resident of Liverpool, England, have invented certain new and useful Improvements in Automatic Telephone Systems, of which the following is a specification.

The present invention relates to improvements in or relating to telephone or like systems and has for its object improved arrangements whereby calls may be dealt with in their proper sequence. More particularly, the invention relates to arrangements in connection with interjunction working between automatic and manual exchanges where the calls from the automatic subscriber are set up on register sets and subsequently brought to the attention of an operator.

One of the features of the present invention is an arrangement whereby the calls are grouped into their proper sequence, that is, in the order in which they arrive prior to the operation of the register sets, while the stored up calls are dealt with in turn by a step by step switching device which might either consist of a mechanical step by step switch or a chain of relays adapted to be operated in succession.

A second feature of the invention consists of a novel arrangement for grouping the calls into a definite order using rotary line switches of the type which remains on the contact last used. A third feature consists of relay switching devices for automatically transferring the stored calls to an indicator or causing the illumination of lamps to enable the operator to ascertain the junction calling and the number required, such transfers taking place one at a time.

These and other features of the invention will be best appreciated by referring to the accompanying drawings, in which Fig. 1 shows circuit connections of a rotary switch and part of the operating circuits of a register set. Fig. 2 shows an arrangement whereby the rotary switches are arranged to seize register sets in a definite order. Fig. 3 shows an arrangement whereby the register sets are successively transferred to an indicator in the order in which they have been set up. Fig. 4 represents the contact spring assembly of a relay employed in Figs. 1 and 3.

Referring to Fig. 1, C represents a rotary line switch of the type in which the wipers remain on the contacts last used which, it is assumed, is associated with a junction line, although it will be understood that this application is only described by way of example, while R represents a register set of which only part is shown. When the junction line is seized, the lead 11 is connected to earth, by arrangements well known to those versed in the art, so that a circuit is closed through the back contact of armature 12 of relay 13, through relay 14 to battery. Relay 14 energizes and at its armature 15 connects earth to one side of relay 13, while at 65 its armature 16 it connects the wiper 17 through the back contact of armature 18 to the other side of relay 13 which is also connected to the magnet 19. The operation consequently depends upon whether the 70 wiper 17 is resting on an earthed contact or not. If it is resting on an earthed contact, then the relay 13 will be short circuited and the magnet 19 will be operated to advance 75 the wipers one step, this operation will be 80 repeated if the next contact wiper 17 comes in contact with is engaged, but eventually, however, an idle line will be reached when the wiper 17 will not rest on an earthed contact. Consequently, relay 13 will energize 85 in series with magnet 19, magnet 19 will not, however, energize in this circuit owing to relay 13 having a high resistance. The energization of relay 13 at armature 18 connects earth to the test wiper 17, at armature 12 the 90 earth on conductor 11 is connected through wiper 20 to relay 21 and battery, at armature 22, relay 13 locks itself energized to lead 11. Relay 14 will fall back on the attraction of armature 12. The lead 23 is extended through 95 armature 24 of relay 13 to wiper 25 and its corresponding contact, armature 26 of relay 21 and its working contact, series relay 27 and magnet 28 of the first of a series of step by 100 step switches adapted to register the number of the calling party. As soon as the subscriber dials the digits which have to be stored, earth impulses are transmitted over the lead 23, thereby causing the energization 105 of series relay 27 and magnet 28 which latter causes the wipers 29 and 30 to step round a number of steps corresponding to the number of impulses transmitted over lead 23. On the first impulse, relay 27 is energized 110 and the wiper 29 moved to the first step.

Wiper 29 thereby closes a circuit for relay 31 which energizes and disconnects the impulse lead at armature 32. The operating circuit is, however, maintained, through armature 32 and its working contact. On the completion of the first series of impulses the relay 27 deenergizes, while the relay 31 remains energized. Consequently, the impulse circuit is continued from armature 26 10 and its working contact through armature 32 and its working contact, armature 33 and its resting contact to the next step by step switch which corresponds in every respect to that just described and serves to record 15 the second impulse. A similar arrangement of relays 31 and 27 is provided with this switch, which enables the impulse circuit to be transferred to a third switch when the previous digit has been completed. Consequently, as many digits may be stored as 20 is desired.

On the relay 27 of the last digit switch falling back an earth is placed on lead 34. This lead causes the energization of relay 25 35 and also lights the register lamp 60.

The above circuit arrangements, which are disclosed in the pending application of Martin et al., Serial No. 367,850, filed March 22, 1920, have been described in order that the 30 operation of the various parts may be understood, as although they form no part of the present invention, yet it is believed that the features of the present invention about to be described will be best understood by reference thereto, as for instance, the invention can be carried into effect by the provision of 35 additional contacts on relays 21, 35, and 36 and suitable circuit connections.

Referring to Fig. 2, the bank of contacts 40 37 represent those contacts which are swept over by the wiper 17, and it will be noted by tracing the chain circuit of the relays 21, each of which corresponds to a different register set, that when one relay 21 is energized, say the first relay, an earth may be 45 traced through armature 38, lead 39 through each of the armatures 40 of the remaining relays 21 to all the contacts of the bank 37 except the second. Thus it will be seen that 50 on a second call coming in, the wiper 17 of the switch used will find earth on the contacts corresponding to all register sets except the second, which it must consequently come to rest upon.

55 The third call coming in, even if the call on No. 1 register set has been attended to but No. 2 is still awaiting attention, will be allocated to the third position and so on. Consequently, every call coming in before 60 others have been attended to will be arranged in a definite order. If, however, only one call comes in at once, then the rotary switches seized will not have to hunt, as all contacts adapted to be swept over by 17 will be disconnected from earth.

Consequently, it will be appreciated, that by this means, the calls will be arranged to seize register sets in the order in which they arrive, and after this order has been arranged, some time will elapse before the dialing operations have been completed when the lead 34 of each register set will be connected to earth and the relay 35 energized. 70

Now, the subsequent operation will be better understood by referring to Fig. 3, in 75 which the relays 35 and 36 of seven register sets are reproduced with their interconnecting circuit arrangements. Assuming relay 35 of the first register set was energized and no others, then a circuit would be closed from 80 battery, armature 41" and its resting contact, armature 42 and its working contact, resistance 43, relay 36 to earth. Although branch circuits are also closed for the other relays 36, these branch circuits are opened 85 at the back contact of armature 45 as soon as the first relay starts to pull up. Accordingly, only relay 36 of the first register set will fully energize. On energizing, this relay 90 closes a locking circuit for itself at armature 44, at armature 45 it connects earth to a common lead connected similarly to the armatures 45 of the relays 36 of the other register sets, while at its armature 46 it disconnects earth from all the other 95 relays 36.

Referring to Fig. 1, it will be seen that in the register set taken by way of example, relay 36 also connects earth at its armature 47 to energize the relays 48, of which one is 100 provided for each of the switching units of a register set. The relays 48 are arranged to connect earth to the contacts selected by the individual switching units, which contacts are connected in multiple with the corresponding 105 contacts of the other register sets, to a bank of lamps common to an operator's position. These lamps are arranged in sets side by side, one set for each switching unit and have numbers thereon corresponding to the 110 position of the contacts in the switch banks. As one terminal of each lamp is permanently connected to battery, the relays 48 on energizing cause the number set up on the register set to be immediately displayed before 115 the operator, while the last relay 48 connects earth to the lead 49 which passes through the wiper 50 to the lead 51 to illuminate a lamp corresponding to the junction with which the rotary switch C is associated. 120 The operator, therefore, sees the number of the party required and the lamp lit at the junction at the same time and thereby has all the information necessary to enable her to complete the connection. Since, the arrangement for displaying register numbers forms 125 no part of the present invention, it has not been considered necessary to show all the circuits concerned in detail, but reference is made to the hereinbefore cited application of 130

Martin et al., as illustrating the preferred arrangement.

Referring to Fig. 3, it will be assumed that, while register set 1 was still awaiting attention, the second register set had been taken into use and also the third, fourth and fifth. Now on relay 36 of the first register set deenergizing, after the operator had attended to the call, only the relay 36 of the second register set will be able to operate, as it will receive current from battery through armature 41 of relay 35 of the first register set and its resting contact through armature 42 of relay 35 of the second register set, resistance 43, relay 36, back contact of armature 46 to earth. The energizing battery of the relays 36 of the third, fourth, fifth and sixth register sets has been removed by the armatures 41 of the relays 35 of the second, third, fourth, and fifth register sets, respectively, which have calls stored up and awaiting attention, and battery is removed from the common conductor at the back contact of armature 45 of relay 36 of the second register set as soon as this relay starts to pull up, as already explained in connection with relay 36 of the first register set. The second call is accordingly dealt with as usual, after which on the deenergization of relay 35 of the second register set, the third call is switched over.

It will be assumed, that by now, two more calls have come in on to the sixth and seventh register sets. The call coming on to the seventh register set removes battery at armature 41' of relay 35 of that set, so that if a further call comes in which will be allocated to the first register set, the relay 36 of that register set cannot energize until the last register set has been dealt with. In order to prevent any possibility of two calls being switched over at once on to the indicator which might arise by one of the calling parties hanging up his receiver before being attended to, the common lead connected to the armatures 45 is provided so that the relay 36 of all positions except that in use will be short circuited.

It is also to be noted that this arrangement has the great advantage, that if two parties are dialling and one should take a longer time to dial than the other, then it is possible to attend to the one who has completed his dialling first even although he should be on the register in advance of the other party; for instance, assuming two subscribers seize the second and third register sets, but the subscriber who has seized the third register set completes his dialling in a much shorter time than the subscriber who has seized the second register set. The operator having dealt with No. 1 register set is then immediately switched on to No.

3 register set as the relay 35 of the second register set will not have energized; then if the party on the second register set completes his number, he will have preference over anyone using the fourth register set, 70 while the subscriber on the fourth register set would be attended to next and the routine would go on in the same order as previously described.

In Fig. 4 the arrangement of the spring contacts of the relay 36 are shown in operative relationship by which it would be appreciated that, on the relay releasing the operations take place in substantially the following order: Firstly the front contact of armature 45 breaks, then armature 46 makes contact; followed by armature 45 making contact with its back contact. Or, considering the reverse operation, on the relay energizing, the back contact of armature 45 breaks first, after which armature 46 breaks its contact and then armature 45 closes its make contact. This adjustment is necessary in order to avoid operating more than one relay 36 at the same time, as will doubtless be understood from the previous explanation. In further explanation, however, it may be pointed out more particularly that it is necessary to have the make contact of armature 45 close last, or after armatures 45 and 46 have separated from their back contacts, in order to avoid grounding the common conductor by partially energized relays such as 36, before such relays are caused to fall back by the opening of the back contact of armature 45 or 46 of the relay 36 which completely energizes. As to the necessity of having armature 45 separate from its back contact before armature 46 breaks its contact, this adjustment becomes essential in a case where calls are waiting on the fifth, sixth, seventh, and first register sets, for example. When the fourth register set is released, and relay 35 of such register set connects battery to relay 36 of the fifth register set, battery is also connected by way of the back contact of armature 45 of this relay to relays 36 of the sixth, seventh, and first register sets. Relay 36 of the fifth register set interrupts the ground connection to relays 36 of the sixth and seventh register sets at its armature 46, so there is no particular danger of these relays pulling up, but it does not interrupt the ground connection to relay 36 of the first register set. On the contrary, the last mentioned relay interrupts the ground connection to the relay 36 of the fifth register set; it is essential, therefore, that armature 45 of relay 36 of the fifth register set separate from its back contact and interrupt the battery to relay 36 of the first register set before the latter relay breaks contact at armature 46 and interrupts ground to relay 36 of the fifth register set. The adjustments described are 125 130

easily made and are entirely effective in preventing the difficulty mentioned.

It will be appreciated, that the invention is equally applicable to mechanical call indicators as to luminous call indicators, for instance, when a limited number of mechanical call indicators are connected by means of rotary switches to junction lines, then they may be arranged to close contacts similar to the contacts closed by relay 35, when all the digits of the number have been registered; then a relay equivalent to 36 will be energized, which would be energized in the order in which the registers have been seized, as previously described. This would effect the illumination of a lamp local to the mechanical call indicator and the illumination of a lamp local to the particular junction line. Conveniently, lamps such as 60 would be controlled by the relay 36 and not by the springs operated on the storage of a number, thereby indicating not only that a call is stored but that a call is stored and should be attended to next.

It will be appreciated, therefore, by means of the arrangement shown in Figs. 2 and 3, the calls are first graded into a proper order, provided that they are not coming in one at a time when no ordering would be required, and they are subsequently dealt with one at a time by means of relays 35 and 36 and suitable interconnecting arrangements as shown. Relay 36 on energizing causes the energization of relays 48 in the register set and performs other similar functions which have been previously referred to.

Having now particularly described and ascertained the nature of my invention and in what manner the same is to be performed, I declare that what I claim is:

1. In a telephone system, hunting switches, lines all normally selectable by said switches, and means for causing the remaining lines to be selected in rotation whenever one or more lines are in use.

2. In a telephone system, a plurality of lines, a plurality of hunting switches adapted to select and connect with said lines at random, and guarding circuits effective only when one or more lines are connected with for causing subsequently operated switches to connect with lines in regular order.

3. In a telephone system, a plurality of lines, a plurality of hunting switches having access to said lines in common, each switch having wipers which normally rest on the last selected line, and guarding circuits effective when any line is in use to cause subsequently operated switches to select other lines in regular rotation.

4. In a telephone system, a plurality of hunting switches, a plurality of lines accessible to said switches in common, all said

lines being normally available for selection, 65 and means rendered effective when any line is selected for rendering all other lines unselectable except the line next in order after the one selected.

5. In a telephone system, a plurality of 70 hunting switches, a plurality of lines accessible to said switches in common, all said lines being normally available for selection, guarding circuits for rendering said lines unselectable, and a relay individual to each 75 line, each relay operating when its associated line is selected to close the guarding circuits for all other idle lines except the line next in order.

6. The combination, with register sets all 80 normally selectable, of means for causing said sets to be selected in rotation whenever more than one is used at the same time, and a consecution controller for causing registered calls to be switched over to a display 85 device one at a time.

7. The combination, with register sets all 90 normally selectable, of means for causing said sets to be selected in rotation whenever a set is already in use, and a consecution 95 controller for causing registered calls to be switched over to a display device in the order in which their registration is completed, provided only one register set at a time is occupied by a completely registered call. 100

8. The combination, with register sets all 105 normally selectable, of means for causing said sets to be selected in rotation whenever a set is already in use, a consecution controller for causing registered calls to be 110 switched over to a display device one at a time, and circuit arrangements in said controller establishing a definite order of preference between register sets occupied by fully registered calls which is independent of 115 the order in which the registration of such calls is completed.

9. The combination, with register sets all 120 normally selectable, of means for causing said sets to be selected in rotation whenever a set is already in use, a consecution controller for causing registered calls to be switched over to a display device one at a time, and circuit arrangements in said controller establishing a definite order of preference 125 between the register sets upon which fully registered calls are waiting and giving such register sets preference over register sets upon which the calls are only partially registered.

10. The combination, with a plurality of register sets and means for operating them to register called telephone numbers, of a consecution controller for causing registered numbers to be switched over to a display device one at a time, said controller having circuit arrangements for establishing a definite order of preference between said regis- 130

ter sets with respect to the order in which any occupied register sets are associated with the display device, and means effective in case all the register sets become occupied 5 at one time for destroying the established order of preference to permit all said register sets to be associated with said display device before any particular set, which ordinarily would have preference over other sets, 10 can be associated with said display device a second time.

11. The combination, with a plurality of register sets and means for operating them to register called telephone numbers, of a 15 consecution controller for causing registered numbers to be switched over a display device one at a time, said controller comprising a start relay and a test relay individual to

each register set, a circuit for each start relay closed when the associated register set is 20 occupied by a completely registered call, a circuit for each test relay connecting one terminal thereof to one pole of the battery, each such circuit including contacts on the associated start relay and contacts on another start relay, a common circuit for connecting the other terminals of all said test relays to the other pole of the battery, and contacts on each test relay except the last included in said common circuit whereby each 30 test relay except the last disconnects all succeeding test relays from the said other pole of the battery.

Signed by me at Liverpool this 4th day of February, 1921.

RICHARD MERGER.
